UNITED STATES PATENT OFFICE.

JOHN A. L. HEROLD, OF RICHMOND, VIRGINIA, ASSIGNOR TO INDEPENDENT AND BENEFICIAL CLUB, INCORPORATED, OF RICHMOND, VIRGINIA, A CORPORATION OF VIRGINIA.

DESIGN FOR A BADGE.

Application filed September 4, 1925. Serial No. 14,709. Term of patent 3½ years.

To all whom it may concern:

Be it known that I, JOHN A. L. HEROLD, a citizen of the United States, residing at Richmond, in the county of Henrico and State of Virginia, have invented a new, original, and ornamental Design for Badges, of which the following is a specification, reference being had to the accompanying drawing, forming part hereof.

Fig. 1 is a plan or face view of a badge showing the design.

Fig. 2 is a side elevation of the badge.

I claim:

The ornamental design for a badge, as shown.

JNO. A. L. HEROLD.
